UNITED STATES PATENT OFFICE.

WILLIAM E. WOODRUFF, JR., OF LITTLE ROCK, ARKANSAS.

ADDRESSING-MACHINE.

SPECIFICATION forming part of Letters Patent No. 224,064, dated February 3, 1880.

Application filed June 16, 1879.

To all whom it may concern:

Be it known that I, W. E. WOODRUFF, Jr., of Little Rock, in the county of Pulaski, State of Arkansas, have invented a new and Improved Addressing-Machine, of which the following is a specification.

Figure 1 is a side elevation of the machine, partly in section, with part of the inking apparatus removed. Fig. 2 is a front elevation 10 of the machine. Fig. 3 is a plan of the same. Fig. 4 is an enlarged plan view of movable bar, friction-rollers, pawl, and other parts related to the main revolving drum. Fig. 5 is a side elevation of the levers, springs, platen, 15 and movable bar through which the device is operated, showing them in position when an impression is being made by the type. Fig. 6 is a perspective view of the case carrying the type. Fig. 7 is a cross-section of the case and 20 type, showing the manner of connection with the band that carries them.

Similar letters of reference indicate corresponding parts.

The object of this invention is to furnish a 25 machine for printing addresses on newspapers, pamphlets, wrappers, envelopes, &c., from movable, consecutive, and connected forms or printing-surfaces.

The invention will first be described in connection with the drawings, and then pointed out in the claims.

Referring to the drawings, A is the table to which the mechanism is attached. B B are two arms rising in a vertical plane from the table, that support between them on a shaft 30 the revolving drum C, whose periphery is provided with grooves, ridges, or teeth a', and to one end of which is secured (or it may be a part of it) the ratchet-wheel b'. D is a fixed 35 upright, slotted near its top, and having within the slot the small friction-roller c', and it is also provided with a sleeve, d', on its rear face.

E is a movable bar that projects downward through the top of the table and works up 40 and down in the sleeve d' in contact with D. In its upper forked end is a friction-roller, f', and in its lower and slotted end is the friction-roller g'. The friction-roller f' bears upward against the beveled end of the pawl F, 45 that rests in the slot of D; below the friction-

roller c' and in the lip h', while the other end of the pawl engages with the teeth of the ratchet-wheel b'. The loop i' prevents the pawl from being thrown out of gear with the ratchet, and the pin k', that passes through it, prevents 55 it from being forced backward too far by the action of the coiled spring l', that connects it with the upright D.

G is a lever pivoted in the staple m', and held by it against the under side of the table. 60 One end of this lever passes through the slot in E, below the friction-roller g', and has attached to it the weight n', while the other end is pivoted to the treadle-rod H. The flat spring o' assists the action of this lever. 65

I is another lever, secured to the under side of the table by the staple p', in which it is pivoted. To one end of it is secured the platen-block K, that plays up and down through a slot or hole in the table opposite, and in the same vertical plane as the axis of the drum C. The front end of this lever is so shaped and disposed as to be under the front end of the lever G, in order that its movements may be controlled by G. The flat spring q' assists in 70 the action of this lever.

Firmly secured to the table is the strong upright frame L, within which are set the grooved, toothed, or ridged drums M and N. On the end of the shaft that carries M, and that projects through a side of the frame, is a small pinion, r', which gears into the cog-wheel O, that is fixed to the drum P and revolves on a shaft projecting from the frame. Above this is another drum, Q, revolving on a projecting horizontal shaft. 80

R is a belt or band, of leather or other suitable material, whose ends are not joined together, that carries the cases S', which hold the types t'. One end of the band is passed over 90 the drum N, and thence over and under the drum C, and thence over the drum M, and the spring-plates U' and V' help to maintain the proper tension of the band by pressing it upon the drums N and M, respectively. The cord W, that is fixed to the drum P and wound around it and the drum Q, carries on its other end a weight, W', whose gravity effects a constant strain upon the pinion r' and tends to draw and keep the band taut. 95

Projecting downward and forward from the top of the frame is the arm A'', carrying the roller B'', above the drum C, while on either side of the said drum are other rollers, C'' and 5 D'', that are supported above the surface of the table by the bent rods a''' and b''', respectively, that pass through their axes.

On the rear end of the roller D'' is a ratchet, c''', in which engages the pawl d''', that is pivoted on the movable bar E. Around these three rollers is passed the endless inking or coloring strip or band E'''.

The cases S' are constructed, as shown in Fig. 6, with a beveled and shouldered groove, 15 f''', cut in the face and extending the whole length thereof, while centrally across this, at right angles, is a rectangular groove, g''', and in the groove f''' is a longitudinal depression, h''', for the reception of the pin i'''. 20 The manner of attaching these to the band R is to apply the groove g''' against the under side of the band, to lay the pin i''' over the same, to press it down into the depression h''', and then to insert the type t', that are in beveled and shouldered form to correspond with the groove f''', into the said groove over the band.

The type may be further secured in the case, if necessary, by spring and catch-pin or other 30 simple device; but this will rarely be required, and in this way the type can be easily attached, firmly secured, and easily removed when desired.

The machine is operated as follows: The 35 cases are made up and attached to the band R, as above described; then one end of the band, free from cases, is passed from the rear of the machine over the drums N, C, and M, in the order herein given, and the inking or coloring 40 band E''' is then or previously inked or colored. The band R may then be drawn over the drums until the type are in position to print upon the articles that will be successively introduced under the inking or coloring bands and over the 45 slot in which the platen plays up and down; then a downward movement of the treadle will cause the lever G to throw up the movable bar E, so that the friction-roller f' shall bear against the beveled end of the pawl F, and, forcing 50 it forward, cause it to turn the drum C and band R through the space of one tooth of the ratchet b', and at nearly the same instant the pawl d''' pushes the drum D'' around for the 55 space of one tooth of the ratchet c''', so that a fresh point of the inking or coloring band may be presented under the type. Continued pressure on the treadle causes the lever G to bear down on the lever I, and, instantly that c''' ceases to turn, force the platen through the 60 slot in the table up against the paper, envelope, or other article laid over the said slot, and press it upward against the type, or rather against the inking or coloring band that covers the face of the type at this point. On the 65 release of the pressure upon the treadle the springs o' and q' and weight n' restore the le-

vers and their attachment to their primary position. By this continuous alternating motion of the treadle the device is operated.

It is often advantageous to insert between 70 the article to be printed upon and the inking or coloring band, so that the article shall not be soiled or defaced, a thin plate of metal or other material with an opening in it of the proper dimensions and shape to admit the printing-surface of the type.

As the work progresses, the band R is drawn rearward over the drum M, and may be rolled up over another drum in the rear, or bestowed in any other convenient manner.

I am aware that it is not new to move by means of a spring-platen the paper or article to be addressed upward against a removable name-block on an endless belt, and that inking-bands have often been used, but not on an 85 addressing-machine, nor otherwise than for stamping dates and business addresses of the persons using them, and not in a machine for addressing missives elsewhere, nor where the paper or thing addressed or printed was 90 pressed upward against an inking or coloring belt interposed between it and the printing-surface.

I do not confine myself to the use of ink on the inking-band, nor absolutely to the ordinary inking-band, for in lieu thereof a coloring-band prepared with oil and lamp-black or oil and other coloring-matter, after the manner of the sheets prepared and used for manifold writing, may sometimes be used to good advantage.

Having thus described my invention, I claim as new and desire to secure by Letters Patent—

1. The within-described addressing-machine, 105 consisting of table A, arms B B, grooved or toothed drum C, slotted upright D, provided with friction-roller c', lip h', and sleeve d', movable bar E, provided with friction-rollers f' and g', pawl F, with beveled end and pin k', ratchet-wheel b', loop i', coiled spring l', lever G, staple m', weight n', treadle-rod H, springs o' and q', lever I, staple p', platen K, frame L, ridged or grooved drums M and N, pinion r, cog-wheel O, drums P and Q, 110 belt or band R, spring-plates U' and V', cord W, weight W', arm A'', roller B'', rollers C'' and D'', rods a''' and b''', ratchet c''', and pawl d''', inking or coloring band E''', and cases S', provided with beveled and shouldered 115 grooves f''', rectangular grooves g''', depressions h''', and pins i''', constructed and arranged substantially as herein shown and described.

2. In an addressing-machine, the combination, with the drum C and roller D''', the ratchets b' and c''', slotted upright D, provided with friction-roller c', lip h', and sleeve d', movable bar E, provided with friction-rollers f' and g', pawl F, with beveled end, and pin k', loop i', 125 coiled spring l', and pawl d''', substantially as and for the purposes described.

3. In an addressing-machine, the combination of the lever G, weight n', spring o', lever I, spring q', and treadle H with the platen K and the bar E, substantially as and for the purpose set forth.
4. The cases S', provided with beveled and shouldered grooves j'''', rectangular grooves
- g''', depressions h''', and pins i''', substantially as and for the purposes described.
